(57) **CLAIM**

The ornamental design for a skin marker, as shown and described.

DESCRIPTION

FIG. 1 is a top plan view of a skin marker in accordance with a first embodiment;

FIG. 2 is a top plan view of a skin marker in accordance with a second embodiment;

FIG. 3 is a left side elevational view of the skin marker in accordance with the first embodiment of FIG. 1;

FIG. 4 is a right side elevational view of the skin marker in accordance with the first embodiment of FIG. 1;

FIG. 5 is a left side elevational view of the skin marker in accordance with the second embodiment of FIG. 2;

FIG. 6 is a right side elevational view of the skin marker in accordance with the second embodiment of FIG. 2;

FIG. 7 is a front elevational view of the skin marker in accordance with the second embodiment of FIG. 2, while a back elevational view thereof is identical;

FIG. 8 is a front elevational view of the skin marker in accordance with the first embodiment of FIG. 1, while a back elevational view thereof is identical;

FIG. 9 is a bottom plan view thereof, of either the first and second embodiment with the carrier strip material shown removed; and,

FIG. 10 is a bottom plan view thereof, of either the first and second embodiment with the carrier strip material shown attached.

The broken line showing is for illustrative purposes only and forms no part of the claimed design.
